SURFACE CONDENSER

Samuel Pennella, Pompton Lakes, N. J.

Application April 5, 1946, Serial No. 660,000

4 Claims. (Cl. 285—45)

1

This invention relates to surface condensers and more particularly to protectors for protecting the inlet ends of condenser tubes against corrosion or erosion.

The cooling water flowing through the tubes of a surface condenser causes failure of the inlet ends of the tubes, due to impingement, erosion, and electro-chemical corrosion, resulting in the eating away and perforation of the tube, causing leakage. Such action has been found by experience to be most severe in close proximity to the inlet end of the tube. It has been the practice heretofore to replace such leaking tubes at a considerable expense both in cost of new tubes, cost of operation of re-tubing of the condenser, and also in the resultant loss of tubes which have only a short part of their entire length rendered incapable of proper operation. Observation of long period of time shows that such corrosion and erosion occurs at the inlet end of the tube and for a relatively short distance from the inlet end and it is an object of the present invention to provide a protector which is associated with the inlet ends of the tubes to protect them from erosion and corrosion, and due to the nature of the material of which the protectors are formed prevent the setting up of electro-chemical action and its resilient corrosion.

Another object of the invention is to provide a protector for the inlet ends of condenser tubes which may be associated with the tube, when the tube is new to prevent corrosion or erosion of the inlet end of the tube or may be associated with a tube after such corrosion or erosion has occurred for the purpose of stopping any leakage from or into the tube and consequently increase the life of the tube.

Another object of the invention is to provide a protector for the inlet ends of the condenser tube which may be installed quickly, inexpensively, and at a minimum labor cost be associated with the tube.

With these and other objects in view, as may appear from the accompanying specification, the invention consists of various features of construction and combination of parts, which will be first described in connection with the accompanying drawings, showing a condenser tube protector of a preferred form embodying the invention, and the features forming the invention will be specifically pointed out in the claims.

In the drawings:

Figure 1 is a longitudinal section through the improved tube protector showing it associated with a fragment of a condenser tube,

2

Figure 2 is an end view of the protector.

Figure 3 is a cross-section taken on the line 3—3 of Figure 1.

Figure 4 is a longitudinal section through a modified form of the tube protector.

Figure 5 is a longitudinal section through another modified form of the improved tube protector.

Figure 6 is a longitudinal section through a still further modified form of the tube protector.

Figure 7 is a cross-section on the line 7—7 of Figure 6.

Figure 8 is a longitudinal section through a further modified form of the tube protector showing its association with a tube which has been eroded.

Figure 9 is a fragmentary longitudinal section through a condenser showing the form of protection illustrated in Figure 8 applied thereto.

Figure 10 is a longitudinal section through a still further modified form of the tube protector.

Referring more particularly to the drawing, Fig. 1 indicates a fragmentary section of a condenser tube sheet and Fig. 2 indicates the inlet end of a water circulating tube associated therewith. The tube 2 is rolled in the tube receiving opening 3 in the tube sheet 1 by attaching the tube 2 to the tube sheet. This is one of the common practices in attaching condenser tubes

to the tube sheets, however in rolling the tubes they are expanded as is clearly shown in Figure 1 of the drawings and such expansion tends to weaken the tubes structurally and produce fatigue so that the resistance of the tube to the destructive force imposed by the water entering the tube is reduced. The shoulder indicated at 4 provided at the junction of the expanded part of the tube with the non-expanded part causes eddies in the water flow which tends to reduce oxygen from the water causing isolated minimum pockets of oxygen which has a high erosion action on the tubes.

Therefore the improved tube protector embodies a sleeve 5 which is constructed of suitable material which is chemically inert with respect to the metal of the tube 2 and the tube sheet 1 and which is slightly resilient and will swell slightly when wetted. The sleeve 5 has a head 6 connected thereto with a drive fit and the head 6 and sleeve 5 are provided with a cooperating shoulder 7 which limits the association of the sleeve into the head. The head 6 preferably formed of plastic or some other hard material which, preferably, is not swellable when wetted and which is chemically inert with respect to the

50
55

metal of the tube 2 and the tube sheet 1. The sleeve 5 has its inner end tapered to substantially knife edge as shown at 8 and when the protector is associated with a tube the sleeve 5 is inserted into the tube so that its tapered portion abuts the shoulder 4 and the bore 9 of the sleeve merges with the bore of the tube 2 without forming an abrupt shoulder or both so as to provide the setting up of small eddies in the water at this point. The head 6 sets tightly against the rolled end 10 of the tube 2 and thus the head 6 and sleeve 5 forms an extending entrance to the tube 2 which extended entrance provides outlet of the tube head 1. In this manner the entrance end of the tube 2 is protected from contact with the water flow into the tube and the resulting erosion and corrosion of the inlet end of the tube is prevented.

Due to the fact that the sleeve 5 is of material which will swell when wetted the protector sleeve 5 may have an outside diameter of such size that it may be easily driven into the inlet end of the tube merely by manual pressure and thus the protector may be quickly and easily attached to condenser tube. As the protector becomes worn and needs replacement it can be bored out of the tube and be replaced with a new one at relatively small cost.

In Figure 4 of the drawing, a modified form of the protector is shown which is adapted for use with condenser tubes which are placed rather than rolled or expanded in the connection with the tube sheets and in this form the condenser tube sheet 10 is counterbored as shown at 11 to receive a placing 12 of any suitable form and the counterbore 11 has its outlet end tapered as shown at 13 to receive the inner-tapered end 14 of the head 15 of the protector. In this form the inner-sleeve 16 abuts the end of the condenser tube 17.

In Figure 5 of the drawing the form shown is similar to that shown in Figure 4 wherein the protector is associated with a placing 18 of any approved type while the inner-tapered end 19 of the head 20 is driven into the tapered end of the counterbore 21 in the tube sheet 22. The sleeve 23, however, is elongated like the sleeve shown in Figure 1 and extends into the condenser tube 24.

Further modified forms of the tube protector are shown in Figures 6 to 9, inclusive, of the drawings. Figure 6 shows one manner of attaching a tube protector to the condenser, while a different manner of attachment is shown in Fig. 8. In this modified form, Fig. 8, the protector comprises the head 25 which is preferably constructed of the same material as the heads 6, 15 and 20 of Figs. 1, 4 and 5, respectively. In Figs. 6 and 8, a sleeve 26, made of swellable semi-resilient material, is driven into the head 25 and its position in the head 25 is controlled by the shoulder 27, which corresponds to the shoulder 7 of Fig. 1. The sleeve 26 is of sufficient length so that it extends into a condenser tube 28, while the inner-flat end 29 of the head 25 has a longitudinal extending recess 31 formed therein extending inwardly from the inner-end of the head.

In Figures 8 and 9, the improved tube protector is shown in use upon the condenser in accordance with my prior Patent 2,298,154 wherein the condenser tubes 32 extend beyond the tube sheet 33 of the outlet end of the condenser so that when the inlet ends of the tubes become eaten away they may be driven forward through the tube sheet 34 at the inlet end of the

condenser. In my prior patent above mentioned, this construction is provided so that the prevented ends of the tubes may be cut off for the purpose of increasing the life of the condenser tube. However, with the use of the protector of the present invention isolated tubes which are found to leak may be driven forward slightly for a short distance and one of the tube protectors mounted thereon for the purpose of stopping the leakage. When such operation is resorted to the inlet of the tube 35 (see Figure 8) is driven to the annular recess 31 in the head 25 while the sleeve 26 extends into the tube 25 a short distance to cover such holes, or corroded spots indicated in 36 in the end of tube. This enables the operator of the power plant in which the condenser is mounted to repair isolated tubes until such time as a sufficient number of the tubes are damaged to warrant the further driving and the cutting off of the defective inlet ends.

In Figure 10 of the drawings a tube protector is shown as formed of a similar piece of material to counterbore of the head sleeves of Figs. 1 and 9, inclusive. In this modified form the tube protector is presented in a form of slightly resilient material which will swell when wetted such as fabric impregnated with plastic but has sufficient resiliency and hardness to maintain its shape and to allow it to be formed without material distortion and in this form the protector includes the sleeve extension 37 which extends outwardly from the inner-end of the head portion 38 sufficiently, for insertion into a condenser tube to protect the inlet end of the tube and the head portion 38 is recessed as shown at 39 as to receive the end of the condenser tube while the inner-end of the head is flat as shown at 40 for facial contact with the condenser tube sheet.

It will be understood that the invention is not to be limited to the specific construction or arrangement of parts shown, but that they may be widely modified within the invention defined by the claims.

What is claimed:

1. A protector for the ends of condenser tubes comprising a sleeve of semi-flexible material having the property of swelling when wetted, an annular head about a portion of said sleeve, said sleeve and head having cooperating annular shoulders thereon for limiting the insertion of the sleeve into the head.
2. A protector for the ends of condenser tubes comprising a sleeve of semi-flexible material having the property of swelling when wetted, an annular head about a portion of said sleeve, said sleeve and head having cooperating annular shoulders thereon for limiting the insertion of the sleeve into the head, said head being constructed of a material which is non-swelling when wetted and both said head and sleeve being constructed of material which is chemically inert with respect to the metal of condenser tube and tube sheet.

3. As a new article of manufacture a protector for the inlet end of condenser tube formed of semi-resilient material which will swell when wetted and which is chemically inert with respect to the condenser tube and tube sheet, said protector comprising an elongated sleeve and an enlarged head on one end of said sleeve and being substantially long with respect to the length of the sleeve, said head provided with an annular recess extending inwardly from an inner-

end and receiving a portion of its condenser tube therein.

4. A protector for the ends of condenser tubes as claimed in claim 2 wherein said head is provided with an annular recess extending inwardly from its inner end for receiving a portion of a condenser tube.
